DOOR HANGER LOCK AND RELEASE

Filed Dec. 30, 1929

UNITED STATES PATENT OFFICE

FRANK G. SCHWARTZ, OF SOUTH MILWAUKEE, AND RUPERT A. NOURSE, OF MILWAUKEE, WISCONSIN, ASSIGNORS TO THE MIDLAND COMPANY, OF SOUTH MILWAUKEE, WISCONSIN, A CORPORATION OF WISCONSIN

DOOR HANGER LOCK AND RELEASE

Application filed December 30, 1929. Serial No. 417,415.

This invention relates to improvements in door hanger lock and release more particularly, although not solely, adapted for baggage car doors.

5 It is one of the objects of the present invention to provide a door hanger lock and release which may be easily actuated in using the door handles for opening and closing the doors.

10 A further object of the invention is to provide a door hanger lock and release in which one of the controlling parts is formed in an open position to be closed around another part.

15 A further object of the invention is to provide a door hanger lock and release which controls the movement of the doors to open or closed or partially closed positions and locks the doors in any of said positions.

20 A further object of the invention is to provide a door hanger lock and release in which doors can be held in partially closed position for safety or ventilation purposes by locating one of the stops at any desired position on the track.

25 A further object of the invention is to provide a door hanger lock and release which is of simple construction, is strong and durable and is well adapted for the purposes described.

30 With the above and other objects in view the invention consists of the improved door hanger lock and release and its parts and combinations as set forth in the claims, and all equivalents thereof.

35 In the accompanying drawings in which the same reference characters indicate the same parts in all of the views:

40 Fig. 1 is a front side view of the improved door hanger lock and release shown mounted on one side portion of a sliding door and supporting track;

45 Fig. 2 is an edge view thereof, parts being shown in section;

50 Fig. 3 is a longitudinal sectional detail view taken on line 3—3 of Fig. 1; and

55 Fig. 4 is a transverse sectional view taken on line 4—4 of Fig. 2.

60 Referring to the drawings the numeral 8 indicates a hanger track upon the upper edge

of which a grooved hanger wheel 9 is mounted. A hanger frame 10 depends from the shaft 11 of the wheel and is adjustably connected to one side portion of a sliding door 12 by bolts 13. Brackets 14 hold the track in spaced position from the wall 15.

The lower outer side portion of the track has mounted thereon a stop member 16 having an upper curved edge 17 and a central locking recess 18. The hanger frame 10, to one side of the periphery of the wheel 9, is formed with a vertically extending groove or channel 19 through which extends a reciprocal bolt 20. The bolt is formed with an inwardly projecting head 21 which extends over and rides on the upper surface of the stop member 16 and drops into the recess 18 to lock the hanger frame and the supported door 12 in closed position as shown. The upper curved edge 17 will, when the door is moved to closed position, raise the bolt 20 so it can automatically drop into locked position. It will be noted that the portion 17' of the stop member projects above the plane of the portion 17 to prevent the bolt from accidentally jumping over the locking recess 18 and passing over the part 17' when the momentum of the movement of the door carries the bolt over the portion 17.

70 A corresponding stop member 16 may be positioned at the opposite end of the track to hold the door in open position.

75 The outer face of the bolt is formed with an elongated recess 22 for receiving an inwardly projecting frame lug 23 and a coiled spring 24. The lug limits the downward movement of the bolt and the spring yieldingly holds the bolt in its lower locking position. An outwardly projecting lug 24' formed on the lower end of the bolt 20 serves 80 to limit the upward movement of the bolt.

85 A strap handle 25 of ordinary construction is mounted on the sliding door 12 below the plane of the hanger frame, and a split tubular handle member 26 which has been closed to extend loosely around said handle is of less length than the handle portion to permit vertical movement of the handle member thereon. The tubular portion of the member 26 is provided with inwardly extending and 90

upper and lower horizontal flanges 27 and 27'. The upper flange 27 is provided with an offset upwardly extending tubular stem 28 for receiving a connecting rod 29 therein. Said rod 29 extends upwardly through a guide 30 and loosely into an opening 31 formed in the lower end portion of the bolt 20 or it may impinge a lower surface of the bolt 20.

10 As thus constructed the use in grasping the handle to open the door will move the handle member upwardly to unlatch the bolt and the door may then be slid to open position. In moving to open position and in 15 the event that a similar stop member is used at the opposite end of the track, the head of the bolt will ride up on the curved portion 17 and drop into the locking recess. In moving the door to closed position the same operation 20 as before described is repeated.

If desired one of the stop members 16 may be mounted on the track intermediate the track ends so that the door may be locked in partially closed position.

25 In moving the door from partially closed position an upward movement of the handle member will unlatch the bolt which will pass over the stop member at the portion marked 17' and the door can be moved to a fully closed position.

From the foregoing description it will be seen that the door hanger lock and release is of very simple construction and is well adapted for the purpose described.

30 What we claim as our invention is:

1. In combination, a track, a door having suspension rollers coacting with said track, a stop member disposed adjacent to said track, a latch carried by said door and co-operable with said stop member, a handle for moving said door located remote from said latch, said handle having an elongated grip portion spaced from said door, a tubular member embracing said grip portion and 40 slidable therealong, said tubular member having a lateral projection extending in close proximity to said door, and a rigid connection between said projection and said latch lying close to said door.

50 2. In combination, a track, a door having suspension rollers coacting with said track, a stop member disposed adjacent to said track, said stop member having a recess and portions of different height disposed on opposite sides of said recess, a latch carried by said door and movable into said stop member recess over the lower of said portions, a handle for moving said door located remote from said latch, said handle having an elongated grip portion spaced from said door, a tubular member embracing said grip portion and 55 slidable therealong, said tubular member having a lateral projection extending in close proximity to said door, and a rigid connection 60 between said projection and said latch lying close to said door.

tion between said projection and said latch lying close to said door.

65 3. In combination, a track, a door having suspension rollers coacting with said track, a stop member disposed adjacent to said track, said stop member having a recess and portions of different height disposed on opposite sides of said recess, a latch carried by said door and movable thereby into said stop member recess over the lower of said portions, and means for releasing said latch 70 from said recess.

In testimony whereof we affix our signatures.

FRANK G. SCHWARTZ. 80
RUPERT A. NOURSE.
